UNITED STATES PATENT OFFICE.

HENRY F. JEROLAMAN, OF CHICAGO, ILLINOIS, ASSIGNOR, BY MESNE ASSIGNMENTS,
TO ALFRED H. SMITH, OF CHAPPAQUA, NEW YORK.

RAILWAY CAR.

Application filed August 18, 1921. Serial No. 493,440.

To all whom it may concern:

Be it known that I, HENRY F. JEROLAMAN, a citizen of the United States, and resident of Chicago, in the county of Cook and State 5 of Illinois, have invented certain new and useful Improvements in Railway Cars, of which the following is a specification.

This invention relates to a novel construction of steel railway cars for the transportation of freight and express matter, and the leading objects of the invention are to expedite the operations of loading and unloading, to facilitate the handling and dispatch of fractional car loads, and to reduce 10 the height, simplify the construction, and lessen the weight of such cars. To these and other ends I have designed a car combining two main novel structural characteristics;—first, an upper-frame or body which 15 rests securely upon, but is unattached to the under-frame, and may be readily lifted therefrom, or set thereon, by suitable hoisting apparatus; and, second, a sectional form of such upper-frame or body, which permits 20 the loading and unloading of the sections separately and independently. Other important structural features reside in the interfitting of the bottom of the upper-frame within and between the side and end sills of 25 the under-frame, the resting of the upper frame directly on the cross-bearers or transoms of the under-frame, the further bracing of the upper and under-frames against 30 relative lateral displacement by vertically 35 slidable telescoping members carried by said parts, respectively, and the construction of the cross-bearers or transoms of the under-frame in arched form, which both reduces the height and facilitates the interfitting of 40 the bottom of the upper frame between the side sills of the under-frame.

My invention and the advantages secured thereby will be readily understood when considered in connection with the accompanying drawings, which illustrate one practical form in which the invention may be embodied, and in which:

Fig. 1 is a top plan view of a railway car constructed in accordance with my invention;

Fig. 2 is a side elevational view of the same, the trucks being conventionally shown;

Fig. 3 is an end elevation on an enlarged scale;

Fig. 4 is a cross-section, on an enlarged 55 scale, on the line 4—4 of Fig. 1;

Fig. 5 is a fragmentary top plan view of the under-frame on the same scale as Figures 3 and 4; and

Fig. 6 is a vertical longitudinal section 60 through an end portion of the car, on the same scale as Figures 3, 4, and 5.

Referring to the drawings, 1 designates the side sills, 2 the center sill (comprising a pair of inwardly facing channels) extending the full length of the under-frame and adapted to house the draft-gear (not shown) at each end, and 3 the end sills; the side and end sills being securely united by overlapping corner brackets 4, as clearly shown 70 in Figures 3 and 5. The side sills 1 are connected at intervals by cross-bearers or transoms 5 that overlie the center sill 2 and are strongly secured thereto by connecting 75 brackets 6 and 7. The end portions of the cross-bearers 5 are bent downwardly, as best shown in Fig. 4, considerably below the horizontal plane of the upper edges of the side sills 1, and are strongly secured to the inner faces of the side sills as by connecting 80 brackets 8. The cross-bearers 5 are, for the most part, shown as T-beams, but certain of them, such as 5* (Fig. 6) are preferably X-beams, for a purpose hereinafter disclosed. To the underside of the center 85 sill 2 is secured, at the proper points, center plates 9 (Fig. 6), such as are commonly used on the underside of the usual body-bolster, the latter being preferably dispensed with in this case, as it is unnecessary.

The upper-frame or body of the car is made in a plurality of independent, box-like sections; four being herein shown, the outer or end sections designated by 10, and the intermediate sections designated by 10*. 90 These sections are all substantially duplicates of each other, and each is, essentially, simply a sheet-steel box having its end, side, and bottom walls suitably braced, as best shown in Fig. 6, the bracing of the bottom 100 wall conveniently consisting simply of transversely disposed angles 11 which rest directly upon and across the center sill 2 between the cross-bearers 5 and 5*; the bottom

wall of the box resting directly upon said cross-bearers 5 and 5^a, as clearly shown in Fig. 6. In this connection it may be noted that the upwardly projecting rib of the cross-bearer 5^a, constitutes a transverse abutment or support for the adjacent ends of two adjacent body sections 10 and 10^a.

By reference to Fig. 4 it will be noted that the described connection of the cross-bearers to the side sills leaves triangular spaces 12 inwardly of the upper edges of the side sills, which spaces are occupied by correspondingly shaped ribs 13 on the lower longitudinal edges of the upper frame, which ribs may conveniently be formed by extending the side walls beneath the floor 14, bending them to proper form, and riveting them to the floor, as shown. This results in the formation of projections which are wedge-shaped in cross section the projections serving to cooperate with the triangular spaces to position the boxes on the frame. With this construction, the upper portions of the side sills and the inclined edges of the cross-bearers cooperate with the ribs in preventing lateral displacement of the upper-frame relatively to the under frame.

To prevent relative longitudinal displacement of the upper and under-frames under sudden pulling and buffing shocks, I provide, in addition to the described X-beam form of cross-bearers 5^a, end posts carried by the under-frame, and, one or more intermediate posts, which are telescopically engaged by parts carried by the sections of the upper-frame. The end posts referred to are shown at 15 and consist preferably of T-beam sections strongly secured at their lower ends in and to outwardly bent sockets 3^a formed in and centrally of the front sills 3, for which purpose the intermediate portion 3^b of each front sill 3 is extended upwardly to approximately the full height of the post, the socket 3^a extending the full height of the central part of said intermediate portion; and to further reinforce the said socket I may also apply reinforcing gusset-plates 16 riveted to and covering the outer surface of the front sill portions 3^a and 3^b, and also reinforcing gusset-plates 17 riveted to the horizontal flanges of the plate 16, the center sill 2, and the main body portion of the front sill 3, as clearly shown in Figs. 3 and 5. The post 15 is secured in its socket by rivets 18. Slidably engaging and cooperating with the inwardly disposed webs of the posts 15 are undercut or dovetail channel strips 19 (Fig. 3) secured to the outer ends of the end sections 10 of the body or upper-frame. Secured to and projecting upwardly from the central portion of the under-frame are a pair of intermediate posts 20 (Figs. 1 and 4) of substantially the same form as the end posts 15; said intermediate

posts being conveniently supported and secured in place by a suitably reinforced vertical web plate 21, itself riveted to one of the cross-bearers 5 of the under-frame. The posts 20 are riveted to each other and to opposite sides of the web-plate 21 by transverse rivets 22; and cooperating with the posts 20 are channel strips 23 secured to the inner ends of the intermediate body sections 10^a. If desired, similar connecting devices may be employed between the sections 10 and 10^a of the body, but this will depend mainly upon the number of sections into which the complete upper-frame or car^a body may be divided in any given case. In a car-body employing four sections, as herein shown, the two end connections and the single intermediate connection are, in practice, sufficient.

Each body-section will be, in practice, provided with a suitable door for opening and closing the same, and I have indicated for this purpose in Fig. 2 the usual sliding-doors 24, but my invention is not concerned with this particular feature of construction.

In the practical use of the car, the same may be loaded and unloaded in the usual fashion through the doorways where the car can be detained for this purpose or where the loading and unloading requires but a limited amount of time. In the principal contemplated use of the invention, however, for the purpose of loading and unloading, each section will be removed from the under-frame by a suitable derrick or hoisting apparatus; and for this purpose the sections are conveniently equipped in their tops with rings or staples indicated at 26 to receive hooks on the hoisting apparatus. In this way, one or more loaded sections can be quickly removed from the under-frame for unloading, allowing other loaded or empty sections to be immediately replaced upon the under-frame, so that the car can be released without having to wait for unloading. As freight cars are frequently delayed many days at a time by the unloading of the same, it will be seen that my invention greatly promotes the prompt handling and dispatch of the cars themselves in service.

It will be noted that the upper and under-frame are not bolted, riveted, or otherwise secured together by fastening means which require to be removed or released before the parts can be separated; the connections being of a purely interfitting or telescoping character, so that the parts can be separated or brought together in secure relation to each other by a simple relatively vertical movement between them.

It will be evident to those skilled in the art that the particular structural details herein illustrated might be considerably modified and varied without departing from

the principles involved or sacrificing any of the benefits and advantages secured thereby. Hence, I do not limit the invention to the exact construction shown except to the extent clearly indicated in specific claims.

I claim:

1. In a railway car, the combination of an under-frame formed with side sills and a plurality of cross-bearers having downwardly inclined end portions attached to said side sills below the upper edges of the latter, and a removable upper-frame seated directly on said cross-bearers and having longitudinal ribs beneath the floor thereof lying between the upper edges of the side sills and the inclined ends of the cross-bearers, substantially as described.

2. In a railway car, the combination of an under-frame formed with side sills and a plurality of cross-bearers having downwardly inclined end portions attached to said side sills below the upper edges of the latter, and a removable upper-frame seated directly on said cross bearers and having its sides extended below the floor and lying inside the upper edges of said side sills, substantially as described.

3. In a railway car, the combination of an under frame composed of side and end sills and cross bearers, the latter having deflected end portions, and a plurality of boxes adapted to be removably seated on said frame and having portions interfitting with the triangular spaces formed by deflecting the end portions of said cross bearers.

4. In a railway car, the combination of an under frame including cross bearers, the end portions of which are deflected to form triangular spaces adjacent to the side sills of the under frame, a plurality of boxes adapted to be removably seated on said frame, said boxes having triangular projections adapted to cooperate with said recesses, and cooperating projections and recesses on said frame and boxes adapted for interfitting engagement by vertical movement of the boxes.

5. In a railway car, the combination of an under frame formed with side sills and a plurality of cross bearers having downwardly inclined end portions attached to said side sills, below the upper edges of the latter, some of said cross bearers between their inclined end portions extending above

the top edges of the side sills and functioning as abutments, and a removable upper frame seated directly on said cross bearers and between the said abutments whereby the said frame is held against displacement under pulling and buffing shocks.

6. In a railway car, the combination of an under frame formed with side sills and a plurality of cross bearers having downwardly inclined end portions attached to said side sills, below the upper edges of the latter, some of said cross bearers between their inclined end portions extending above the top edges of the side sills and functioning as abutments, and a removable upper frame seated directly on said cross bearers and between the said abutments whereby the said frame is held against displacement under pulling and buffing shocks, said upper frame having longitudinal ribs beneath the floor thereof lying between the upper edges of the side sills and the inclined ends of the cross bearers.

7. In a railway car, the combination of an under-frame formed with side sills and a plurality of cross bearers having downwardly inclined end portions attached to said side sills below the upper edges of the latter, some of said cross bearers having a flange extending above the top edges of the side sills between the said downwardly inclined ends functioning as abutments, and a removable upper frame adapted to be seated directly on said cross bearers and between said flanges whereby the said frame is held against displacement under draft and buffing strains.

8. In a railway car, the combination of an under-frame formed with side sills and a plurality of cross beams having downwardly inclined end portions attached to said side sills below the upper edges of the latter, some of said cross bearers being X beams extending above the top edges of said side sills and functioning as abutments, and a removable upper frame adapted to be seated directly on said cross bearers and between the said X bearers, whereby the frame is held against displacement under draft and buffing strains.

Signed at Chicago, Illinois, this 12th day of August, 1921.

HENRY F. JEROLAMAN.
